DISPLAY MOTORS

Sheldon M. Wengel, Reedsburg, Wis.

Application March 7, 1956, Serial No. 570,146

3 Claims. (Cl. 310—21)

This invention relates to improvements in display motors intended primarily for use in actuating display devices, such as those used for advertising purposes, wherein a movable part carrying the advertising is actuated by the motor.

In United States Letters Patent No. 2,598,954, issued to me on June 3, 1952, there is described and claimed a display motor adapted for use with an oscillatory advertising device which is actuated by the intermittent and automatic energization of a solenoid arranged to repel a magnet in such a manner that repeated impulses are imparted to the device in response to its own movements. Such a display motor is conveniently operated by a dry cell battery which may be removed to discontinue its operation.

The principal object of the present invention is to provide a display motor which operates on the same principle as the one referred to above but which produces a rotary motion of the display device instead of an oscillatory movement thereof. A further object of the invention is to provide a display motor of the type referred to in which intermittent impulses derived from an oscillatory member are utilized to impart a continuous rotary motion to a display device. Still another object of the invention is to provide a display motor comprising an oscillatory part adapted to be actuated by the intermittent energization of a solenoid and arranged to operate through novel clutch mechanism to effect a continuous rotary motion of a movable part. Other objects relate to various features of construction and arrangement which will appear more fully hereinafter.

The nature of the invention will be understood from the following specification taken with the accompanying drawings in which one embodiment of the invention is illustrated. In the drawings,

Figure 1 shows a front elevation of the improved display device embodying the present invention;

Fig. 2 shows a vertical section taken on the line 2—2 of Fig. 1;

Fig. 3 shows a vertical section on a reduced scale taken on the line 3—3 of Fig. 2;

Fig. 4 shows a diagrammatic view of the electric circuit by which the motor of the present invention is operated;

Fig. 5 is a perspective view of the motor shown in Figs. 1 and 2 with the display disk removed;

Fig. 6 shows a front elevation of the motor shown in Figs. 1 and 2, illustrating the positions of the parts at different stages of the operation of transforming an oscillatory motion into a rotary motion; and

Fig. 7 is a partial front elevation, similar to that of Fig. 6, showing a modified form of the invention.

The present invention is adapted for use in actuating a display card used for advertising purposes and the present invention differs from that disclosed in the prior Letters Patent referred to above in that the display card 10 carrying the advertising material is adapted to be rotated continuously in the same direction by a display

2

motor which causes an oscillatory motion to be transformed into a rotary motion. The display motor comprises a U-shaped frame member 12 comprising a bottom wall 12a and upwardly extending parallel side walls 12b and 12c. The bottom wall 12a is secured to a channel shaped member 13 which in turn is secured to the upper arms 14a of two other U-shaped frame members 14, each comprising two parallel horizontal arms 14a and an upwardly extending back wall 14b. The side walls 14a of the lower frame members are provided with projections 15 which are adapted to be snapped into engagement with the terminal posts of two dry cell batteries 16 which are utilized to supply the electric power for actuating the movable parts of the motor as hereinafter described. The batteries are connected in series by a conductor 17 which is attached to the lower terminal posts. The upright walls 14b of the lower frame members are spaced apart by sleeves 18 mounted on pins or rivets 19.

The upper extremities of the vertical frame members 12b and 12c are spaced apart by pins 20 and there is journaled in the upper parts of these frame members a pivotally mounted shaft 22 having on the forward side of the front frame member 12b a crank arm 22a which is adapted to oscillate in a vertical plane and which terminates in a forwardly extending part 22b. Washers 23 are secured to the shaft 22 on the outer sides of the two frame members 12b and 12c, as shown particularly in Fig. 2, thus holding the shaft against endwise displacement. Between the two frame members 12b and 12c there is a plate 24 having upstanding ears 24a which are secured to the shaft 22. This plate is also secured by means of sleeves 24b to the horizontal portion 25a of an actuating member 25 which is adapted to have pivotal movement in a vertical plane about the axis of the shaft 22. The actuating member comprises a semicircular portion 25b which is connected at its ends with the straight portion 25a and which is adapted to be oscillated when the motor is in operation.

The semicircular portion 25b of the actuating member is substantially straight in its middle portion, as is shown at 25c in Fig. 3, and this straight portion has secured thereon a permanent magnet 26 in the form of a tubular sleeve closely fitted by the portion 25b of the actuating member and this magnet is adapted to oscillate in the magnetic field of a solenoid 27 which is mounted in fixed position between the arms 12b and 12c of the frame 12 and which is adapted to be energized periodically in response to the oscillation of the magnet 26 with the actuating member 25. The solenoid 27 is constructed about a central insulating sleeve 28 and between the insulating end plates 29, and the actuating member 25 and the magnet 26 are preferably so arranged that the magnet will form the core of the solenoid and will operate through the tubular insulating member 28.

The plate 24 which carries the actuating member 25 has secured thereto, beneath the shaft 22, a depending contact member 30 which is adapted to be overlapped to a limited extent by the upper end of a flexible contact member 31 which is secured by brackets 32 to the upper side of the solenoid 27 from which it is suitably insulated. In order to prevent excessive vibration of the contact spring 31, a sheet of felt 33 or the like is slit longitudinally and passed into engagement with the contact spring, as shown in Figs. 2 and 3, between the fixed support of the spring and the free upper end thereof. It has been found that this sheet of felt, which bears against the frame member 12b at its upper end and which bears on the solenoid at its lower end (the lower end of the felt sheet having been broken away for clarity), is effective in preventing undue vibration of the contact

spring so that the oscillatory device operates with a minimum of noise.

The electric circuit by which the solenoid 27 is energized is illustrated diagrammatically in Fig. 4 where the solenoid 27 surrounding the electromagnet 26 is connected in series with the two batteries 16. These batteries are connected to the ground, as shown at 34, and a conductor 35 leads from the batteries to the upper contact spring 30 which is adapted to engage the movable contact spring 31 to establish a connection with the other terminal of the solenoid.

When the contacts 30 and 31 are engaged, the circuit shown in Fig. 4 is completed and an impulse is imparted to the actuating member 25 as a result of the reaction between the solenoid and the permanent magnet 26. The contact spring 31 is of substantial length and is adapted to retain contact with the stationary contact member 30 through a limited arc of travel of the contact member 31, whereupon the contact is broken, the solenoid 27 is de-energized and the magnet 26 and the shaft 22 are returned by gravity to their initial positions. This causes the contact between the members 30 and 31 to be again completed and the solenoid 27 again energized so that a new impulse is imparted to the actuating member 25 and the shaft 22, thereby moving the shaft 22 through a substantial angle in the opposite direction.

For illustration of the operation just referred to, let it be assumed that the permanent magnet 26 is magnetized with its south pole to the right and its north pole to the left as viewed in Fig. 3 and that the solenoid 27 is wound so that energization thereof produces a south pole at the right end thereof and a north pole at the left end thereof, whereby the respective poles of the magnet 26 and the solenoid 27 will repel each other. Assuming that this reaction causes the magnet 26 and the actuating member 25 to be swung, for example, to the left, as viewed in Fig. 3, as soon as the south pole of the magnet 26 passes the center of the solenoid 27, the north pole of the solenoid will begin to attract the south pole of the magnet to give further impetus to the movement of the magnet toward the left. Before the right end or south pole of the magnet reaches the left end or north pole of the solenoid, the contacts 30 and 31 separate and interrupt the circuit of the solenoid, but the magnet 26, due to its momentum, continues to swing toward the left beyond the end of the solenoid. When the peak of this left-hand swing is reached, the magnet swings toward the right due to gravity until the contacts 30 and 31 again engage each other at the center of the swing to close the circuit of the solenoid 27 again. The south and north poles of the magnet 26 will now be repelled toward the right by the respective south and north poles of the magnet and the north pole of the magnet will be attracted by the south pole of the solenoid, so that the magnet and the solenoid then swing toward the right. Before the magnet reaches the end of its swing toward the right, the contacts 30 and 31 are again separated and the solenoid is again de-energized. The magnet then continues its swing due to its momentum and, when it reaches the end of its travel, it returns by gravity to its center position where the contacts are again closed and the cycle is repeated.

The oscillatory motion of the actuating member 25, which is imparted thereto by the magnet 26 and which goes on continuously as long as the batteries 16 are in place in the frame members 14, is utilized to effect a continuing rotary motion in the same direction of the display device 10. This display device is fixed on one end of a shaft 40 which is journaled in bearings formed in the upright frame members 12b and 12c and the end of the shaft opposite the display device 10 has secured thereon a circular disk 41 having a hub 41a which is secured to the shaft by a set screw 41c. This disk has an annular friction surface 41b through which impulses are imparted to the disk to effect the rotation of the shaft 40 and the display device 10.

The rotation of the disk 41 is effected by impulses which are transmitted thereto from the oscillatory crank arm 22a of the shaft 22 which is oscillated through forward and reverse strokes by the actuating member 25. The outer extremity 22b of the crank arm 22a is pivotally connected to a bar 42 which extends laterally therefrom with its other end pivotally connected to an arm 43 arranged to extend downwardly toward the disk 41. The lower end of the arm 43 has secured thereto a driving member 45 having side flanges 45a which are pivoted at 46 to a U-shaped bracket 47. This bracket has its side flanges pivoted on the shaft 40 and it is adapted to swing in a vertical plane with the driving member 45. The driving member 45 is preferably formed of relatively soft metal, such as Phosphor bronze, and it is provided with a lower extremity 45b in the form of a projecting flange having a lower edge which is adapted to engage the surface 41b of the disk 41. When the arm 43 is swung toward the left, as viewed in Fig. 6 in response to a corresponding movement of the arm 22a of the shaft 22, the extremity 45b of the driving member is adapted to engage the surface 41b of the disk 41 and causes it to rotate in a counterclockwise direction as indicated by the arrow 48 in Fig. 6, where the extreme left-hand positions of the parts are illustrated by the dotted lines 49. This driving action of the member 45 upon the disk 41 continues as long as the lower end of the arm 43 continues its motion toward the left and, when the motion of the arm 43 is reversed, due to a reverse movement of the oscillatory actuating member 25, the driving member 45 is retracted from the surface of the disk 41 and moves toward the right, as viewed in Fig. 6, to the extreme position shown by the dotted lines 49. When the arm 43 again moves toward the left, due to a reversal of the actuating member 25, the driving member 45 again engages the surface of the disk 41 and imparts a new driving impulse thereto. In this way the disk 41 and the display device 10 are rotated continuously in the same direction by successive increments of movement which are imparted thereto by the reciprocatory movement of the driving member 45.

The frame 12 may be provided with metal clips 50 which are offset with respect to the wall 12b so that they may be passed over supporting members 51, as shown in Fig. 2, to hold the motor in the desired position for display purposes. The mass of the parts carried by the shaft 40 is such that this shaft will ordinarily be rotated with a smooth continuous motion even though the driving member 45 engages the disk 41 only intermittently. This arrangement has the advantage that a driving force is applied by the member 45 only to the extent necessary to maintain a substantially constant speed of the disk and the shaft. If desired, the disk may be supplied with an annular series of ratchet teeth and a ratchet may be arranged to engage these teeth to prevent reverse rotation of the disk 41 between successive feeding operations of the member 45 but this provision has not been found to be necessary.

In Fig. 7 of the drawings, there is illustrated a modified form of the apparatus for transforming the oscillatory motion of the shaft 22 into the rotary motion of the shaft by which the display device is rotated. In this form, the shaft 22, operated by the actuating member 25 in the manner previously described, has the extremity 22b of its crank arm 22a arranged to engage a slot 55a in a driving member 55. This driving member has a transversely directed curved flange 55b adapted to engage the peripheral surface 56a of the disk 56 fixed on the shaft 40 and it has a lateral extension 55c which is pivoted at 57 in an arm 58. This arm has an extension 57a pivoted on the shaft 40 and it extends upwardly in an inclined position in the same vertical plane as the driving member 55. When the crank arm 22a is oscillated toward the right as viewed in Fig. 7, the driving member 55 moves bodily in the same direction and its flange 55b

bears on the surface 56a of the disk to rotate the disk in the direction of the arrow 59. Then, when the crank arm 22a oscillates in the other direction, the driving member 55 is swung toward the left as viewed in Fig. 7 with the result that the flange 55b moves out of engagement with the surface of the disk 56 and the upper part of the member 55 engages the arm 58 to swing it toward the left, thereby locating the flange 55b in a new position in preparation for the next driving stroke of the member 55.

Although two forms of the invention have been shown and described by way of illustration, it will be understood that it may be constructed in various other embodiments which come within the scope of the appended claims.

What is claimed is:

1. A display structure comprising a frame, a shaft mounted for rotation on said frame, a display device mounted on said shaft for movement therewith, a disc mounted on said shaft for movement therewith and having a friction surface on the periphery thereof, an arm pivotally mounted on said frame and spaced from said shaft, electrically actuated means for imparting oscillatory movement to said arm, a driving member having one end thereof pivotally connected to said arm and having on the other end thereof a part frictionally to engage said friction surface, a bracket pivotally mounted on said shaft at one end and pivotally connected to said driving member at the other end, movement of said arm in one direction causing said driving member and said bracket to pivot and to move said part into frictional engagement with said friction surface to drive said disc in said one direction and movement of said arm in the other direction moving said part out of engagement with said friction surface to permit said disc to continue rotation in said one direction, said electrically actuating means oscillating said arm whereby said part imparts driving impulses to said disc when the rate of movement of said part along said friction surface is greater than the rate of movement of said friction surface when said arm is moved in said one direction, whereby to cause said disc and said shaft and said display device to be rotated at a substantially constant speed by said oscillatory movement of said arm.

2. A display structure comprising a frame, a shaft mounted for rotation on said frame, a display device mounted on said shaft for movement therewith, a disc mounted on said shaft for movement therewith and having a friction surface on the periphery thereof, an arm pivotally mounted on said frame and spaced from said shaft, electrically actuated means for imparting oscillatory movement to said arm, a driving member, a bar interconnecting said arm and one end of said driving member, the other end of said driving member having a part thereon frictionally to engage said friction surface, a bracket pivotally mounted on said shaft at one end and pivotally connected to said driving member at the other end and intermediate the ends of said driving member, movement of said arm in one direction causing said driv-

ing member and said bracket to pivot and to move said part into frictional engagement with said friction surface to drive said disc in said one direction and movement of said arm in the other direction moving said part out of engagement with said friction surface to permit said disc to continue rotation in said one direction, said electrically actuating means oscillating said arm whereby said part imparts driving impulses to said disc when the rate of movement of said part along said friction surface is greater than the rate of movement of said friction surface when said arm is moved in said one direction, whereby to cause said disc and said shaft and said display device to be rotated at a substantially constant speed by said oscillatory movement of said arm.

15. 3. A display structure comprising a frame, a shaft mounted for rotation on said frame, a display device mounted on said shaft for movement therewith, a disc mounted on said shaft for movement therewith and having a friction surface on the periphery thereof, an arm pivotally mounted on said frame and spaced from said shaft, electrically actuated means for imparting oscillatory movement to said arm, a driving member having a slot therein pivotally and slidably to receive said arm, a part formed on the other end of said driving member frictionally to engage said friction surface, a bracket pivotally mounted on said shaft at one end and extending toward said arm, means pivotally interconnecting the other end of said driving member to said bracket intermediate the ends of said bracket, the other end of said bracket extending upwardly adjacent to said arm, movement of said arm in one direction causing said driving member to pivot to a position to move said part into frictional engagement with said friction surface to drive said disc in said one direction and movement of said arm in the other direction moving said part out of engagement with said friction surface and moving said driving member into contact with said bracket to permit said disc to continue rotation in said one direction, said electrically actuating means oscillating said arm whereby said part imparts driving impulses to said disc when the rate of movement of said part along said friction surface is greater than the rate of movement of said friction surface when said arm is moved in said one direction, whereby to cause said disc and said shaft and said display device to be rotated at a substantially constant speed by said oscillatory movement of said arm.
